UNITED STATES PATENT OFFICE.

FELIX S. TOWLE, OF NEW YORK, N. Y., ASSIGNOR TO JAMES E. HAMMILL,
OF SAME PLACE.

BOTTLE-STOPPER.

SPECIFICATION forming part of Letters Patent No. 499,898, dated June 20, 1893.

Application filed January 23, 1893. Serial No. 459,402. (No model.)

To all whom it may concern:

Be it known that I, FELIX S. TOWLE, a citizen of the United States, and a resident of New York, in the county of New York and State of New York, have invented certain new and useful Improvements in Bottle-Stoppers, of which the following is a specification.

The invention relates to improvements in bottle stoppers or caps, and particularly to the class of stoppers or caps in which the stopper consists of a tin disk secured to a swinging bail and adapted to be locked upon the mouth of the bottle or jar by a lever. Heretofore the tin cap has been secured to the swinging bail by means of a grooved disk soldered at its opposite edges to the top of the cap and inclosing between itself and said cap the middle portion of the bail. It is intended that the tin cap shall be loose on the bail so as to be capable of turning freely thereon.

My present invention relates particularly to a new means for securing the tin cap to the middle part of the swinging bail, and its object is to obviate certain defects in the caps or stoppers as heretofore made.

The method heretofore in use of securing the tin cap to the swinging bail by a soldered disk is defective in many particulars, and it may be mentioned that the preparing and soldering of the disk involves an undue expense and that in applying said disk the solder frequently enters the groove for the bail and fastens the latter so that the cap will not turn thereon, thus rendering the structure useless.

In accordance with my invention I remedy the foregoing defects and objections and produce a stopper in which the soldered disk is wholly dispensed with the wire bail secured by integral portions of the tin cap being closed over its middle portion.

The invention will be more fully understood from the detailed description hereinafter presented, reference being had to the accompanying drawings, in which—

Figure 1 is a central vertical section of the upper portion of a bottle or jar having applied thereto a stopper or cap constructed in accordance with and embodying the invention. Fig. 2 is a detached top view of the tin cap as it appears after the first operation in

the manufacture, showing a raised central portion containing a transverse groove to receive the middle portion of the wire bail; Fig. 3 a central vertical section of same on the dotted line 3—3 of Fig. 2; Fig. 4 a top view of same showing the wire bail in place, this view representing the tin cap after it has been subjected to the second operation in the manufacture, viz: the moving of the opposite sides of the central elevated portions of the cap toward each other to close the transverse groove over the wire bail; Fig. 5 a central vertical section of same on the dotted line 5—5 of Fig. 4; and Fig. 6 is a detached central vertical section on an enlarged scale of the central portion of the sheet metal cap showing by solid lines the form of same after the first operation in the manufacture and by dotted lines the condition of the transverse groove after the second operation in the manufacture.

The essential features of the invention relate to the sheet metal cap A and the wire bail B, and these will preferably be secured to the neck of the bottle or jar by the well known form of lever shown. The cap A is formed from a single piece of metal with the elevated central portion a, the transverse groove b, and the encompassing bearing flange d, as shown in Figs. 2 and 3, which show the condition of the cap after the first operation in its manufacture. The transverse groove b is of a size adapting it to freely receive the middle portion of the wire bail B, whose lower depending ends are pivotally secured in the usual manner.

After the cap A has been produced in the form shown in Figs. 2 and 3, the bail B is placed in the transverse groove b and there properly secured by pressing the opposite sides of the central elevated portion a toward each other, thus closing the groove b around the bail and firmly securing the latter in place, as shown by dotted lines in Fig. 6 and solid lines in Figs. 4 and 5. The pressing toward each other of the opposite sides of the central elevated portion a constitutes the second and final operation in the manufacture, and hence it will be seen that by the two operations the cap is formed and secured to the

bail without the use of solder or the extra disk heretofore employed to hold the bail and cap together.

By means of my invention the method of manufacturing the stopper is rendered more efficient and greatly simplified and cheapened, and the stopper as an article of manufacture is improved and enhanced in value.

What I claim as my invention, and desire to secure by Letters Patent, is—

In a bottle stopper and cap having the central portion *a* and closed transverse groove *b*

the whole being formed of one piece of metal, combined with the wire bail *B* held in said groove; substantially as and for the purposes set forth.

Signed at New York, in the county of New York and State of New York, this 26th day of November, A. D. 1892.

FELIX S. TOWLE.
